UNITED STATES PATENT OFFICE.

FLOYD WATERMAN, OF NEW LISBON, WISCONSIN.

CAM FOR INTERNAL-COMBUSTION ENGINES.

1,280,912.

Specification of Letters Patent.

Patented Oct. 8, 1918.

Application filed August 1, 1916. Serial No. 112,583.

To all whom it may concern:

Be it known that I, FLOYD WATERMAN, a citizen of the United States, residing at New Lisbon, in the county of Juneau and 5 State of Wisconsin, have invented new and useful Improvements in Cams for Internal-Combustion Engines, of which the following is a specification.

This invention relates to cams especially 10 designed for operating the valves of internal combustion engines of the four cycle type, the object of the invention being to produce a cam which will render possible extra high engine speed, insure the opening 15 and closing of either the intake or exhaust valve with which it is associated and accurately time the period during which the valve is sustained in an open position as well as the period in which the valve is 20 sustained in a closed position.

A further object in view is to dispense 25 with the usual expensive cam shaft and also obtain greater efficiency in the horse power delivered by the engine by the employment of lighter valve closing springs which are rendered possible by the cam of this invention, said cam operating in both directions on the tappet or push rod in contradistinction to the present valve operating 30 mechanism, wherein the valve is opened positively but depends entirely upon the valve seating spring for its closing operation.

With the above and other objects in view, 35 the invention consists in the novel construction, combination and arrangement, herein fully described, illustrated and claimed.

In the accompanying drawing:

Figure 1 is a face view of a cam embodying 40 the present invention showing the switch in one of its two positions.

Fig. 2 is a similar view showing the switch in its other position.

Fig. 3 is a diametrical section through the 45 same on the line 3-3 of Fig. 1.

In the preferred embodiment of this invention, the body 1 of the cam is of generally cylindrical formation as shown in Figs. 1 and 2. In the working face of the body 50 1, the latter is formed with a camway or guideway of special configuration, said camway embodying a generally annular valve closing run or portion 2, a valve opening run or portion 3, an oblique connecting passage 4 between the runs 2 and 3, and another

oblique passage 5 connecting said runs 1 and 2.

6 designates a switch which is mounted on a pivot 7 and which oscillates back and forth between the runs 2 and 3. The switch 6 is provided with an arm 8 having a working face 9 against which, in the preferred embodiment of this invention travels a roller 10 on the valve operating connection 11 which may consist either of the usual tappet or push rod or the valve stem itself. 65

In addition to the arm 8, the switch 6 comprises a projection 12 and another projection 13, the projection 12 being adapted to extend into the run 2 and the projection 70 13 being adapted to extend into the run 3 as illustrated in Figs. 1 and 2. The switch 6 is held at either limit of its movement by means of a spring 14 which is of the bowed type, one end thereof being connected at 75 15 to the switch and the other end thereof being connected at 16 to a fixed point of the body 1. The points of attachment 15 and 16 are so arranged with respect to the pivot 7 of the switch 6 that when the switch is in the position in Fig. 1, the point 15 lies on the inner side of the imaginary line drawn through the points 7 and 16. When the switch is in its other position as shown in Fig. 3, the point 15 lies at the outer side of 80 an imaginary line drawn through the points 7 and 16. Therefore the spring 14 acts to hold the switch 6 in the position shown in either of said figures. 85

The body 1 of the cam is mounted fast on 90 a cam shaft 17 and is shown as connected thereto by means of a key 18.

In operation, starting at the point *a* the roller 10 travels in the direction of the arrow along the dotted line of Fig. 1 until it comes 95 in contact with the projection 12 against which it acts to shift the switch from the position shown in Fig. 1 to the position shown in Fig. 2. It then continues along the dotted line *b* of Fig. 2 until it makes 100 nearly a complete circle whereupon it travels along the working face 9 of the arm 8 of the switch and meets the projection 13, the result being that the switch is again shifted to the position shown in Fig. 1. The passage 5 causes the valve to be shifted to an open position by causing the roller 10 to move from the run 2 into the run 3. The passage 4 causes the roller to move from the run 3 back into the run 2 thereby closing 110

the valve. During the two revolutions of the crank shaft and the cam shaft, the roller 10 occupies the run 2 for approximately one and one-half revolutions of the crank shaft and said roller occupies the run 3 for approximately one-half of the revolutions of the crank shaft. Thus the valve is opened and sustained in an open position once in each two complete revolutions of the crank 10 shaft which is necessary to the proper operation of a four cycle internal combustion engine.

The body 1 is formed with a recess 19 to receive the free extremity of the arm 8 15 when the latter moves outwardly and the body is also cut away to form a recess 20 for the projection 12 when the switch 6 is in the position shown in Fig. 2.

It will be understood that the cam operates with a pulling as well as a pushing operation on the push rod and therefore a lighter or weaker spring may be used for closing the valve and holding the same against its seat. In a multiple cylinder engine embodying an inlet and exhaust valve for each cylinder, a considerable amount of load is thus taken from the cam shaft 17

resulting in higher efficiency and power in the engine.

I claim:

A valve operating cam for internal combustion engines, comprising a runway embodying an annular portion, the inner wall of which is in the form of a true circle, and a segmental portion described on the same center but of different radius terminally communicating with the annular portion by means of connecting passages, said segmental portion extending not to exceed one hundred and eighty degrees, a switch pivotally mounted in one of said connecting passages and having a projection adapted to extend into the annular portion of the run and also having a projection adapted to extend into the segmental portion of the run, and means for yieldingly sustaining said switch in either position to direct a valve actuating member alternately into the annular run and the segmental run, whereby the engine valve is opened only once in two revolutions of the engine shaft.

In testimony whereof I affix my signature.

FLOYD WATERMAN.
